[57] CLAIM

The ornamental design for a nutcracker, as shown and described.

DESCRIPTION

FIG. 1 is a front elevational view of a nutcracker showing our new design, the opposite side being a mirror image;

FIG. 2 is a top plan view thereof;

FIG. 3 is a left side elevational view thereof, the opposite side being a mirror image;

FIG. 4 is a bottom plan view thereof;

FIG. 5 is a cross-sectional view thereof taken along line 5—5 of FIG. 3; and,

FIG. 6 is a vertical cross-sectional view thereof in an open position.

FIG. 1

FIG. 2

FIG. 3

FIG. 4
